UNITED STATES PATENT OFFICE.

PAUL PUGNIET, OF PARIS, FRANCE.

STOCKING-SUSPENDER.

1,348,444.

Specification of Letters Patent. Patented Aug. 3, 1920.

Application filed July 24, 1919. Serial No. 313,125.

To all whom it may concern:

Be it known that I, PAUL PUGNIET, a citizen of the French Republic, residing at Paris, France, have invented new and useful Improvements in Stocking-Suspenders, of which the following is a specification.

In a suspender the connecting piece between elastic or resilient material and the stocking is in the form of a metallic support 10 consisting of a ring-portion of appropriate contour to which is connected the elastic material, the ring being formed with a metal member and provided with a buckle or similar fitting adapted to engage with a button 15 over which the edge of the stocking is placed.

The said metallic support forms the joint of the suspender and has much disadvantage.

For example in a known construction the arrangement of retaining the flexible portion 20 of the stocking clip is unsatisfactory because the pull has its effect on the connection which will not stand constant use so that the suspender very soon becomes useless.

25 The connections of this type have also the disadvantage of presenting metal portions, badly adjusted and more or less badly fitted by worn tools, when the pull of the flexible portion takes effect. These metallic parts 30 when in contact with the stocking wear out the same or give annoyance to the wearer of the suspender. Moreover these systems of attachment also ruin the elastic which becomes cut at such places and after a short 35 time breaks, and the flexible portion becoming worn out by rubbing on the metal clips becomes quickly cut through and detached from the support thus rendering the stocking clip useless. Moreover the ends of the 40 flexible loop are liable to become detached from the support. The deteriorating effect is considerable because when fitting the parts together the branches become cut through against the metal where the two are 45 connected together, it being impossible at this place to turn the edge of the metal over. Other known arrangements have similar drawbacks from the fact that the buckle or clip retaining the stocking is held in place 50 by pressure of some kind which gives rise to wear and rapid deterioration and want of solidity.

The present invention has for object the provision of a connecting piece serving to join or bind and fix the two extremities of the lower flexible portion of a stocking re-

taining clip which will obviate the above named disadvantages.

According to this invention the solidity of the connection is perfect because the 60 strain is no longer on the individual parts but on the support itself which enables a lighter or thinner metal to be used with consequent saving in cost of production. The present arrangement further allows the two 65 branches of a flexible body of any kind to be placed closer together in a conical member having the form of a sleeve and leaving sufficient freedom for the two branches but only limiting the opening of the buckle or clip 70 portion and preventing any deterioration whatever since the edge of the sleeve is turned over, and being capable of exercising but a slight pressure on the flexible connection. 75

This is an essential feature in the case of an elastic and flexible connection, the elastic keeping its elasticity inside the sleeve over its entire length. On the other hand on the body portion itself of the support any very 80 strong joint can be made: a slit for the introduction of a bow, raised teeth which can subsequently be pressed down, upturned hook, or an additional piece can be fitted and so on because no matter what the defects may be: projections, rough edges, easy unhooking, of the means employed, these faults disappear in the recess or depression formed by the two shells which, engaging 85 with the branches of the support on tightening inclose the whole and enhance the solidity of the fixing means and leave only rounded edges. The fixing of the flexible portion to the body of the support being independent of the tightening of the two 90 shells, the manufacture is simplified and the solidity of all the parts made can be insured and no strain on the connecting piece can take place by any pull on the buckle or clip 95 which is of flexible material. 100

It will readily be seen that with this arrangement the extremities of a flexible body can be securely attached and provide a rigid clip covered with rubber, fabric or other suitable material which will in no way spoil 105 the stockings.

The invention is shown by way of example in the accompanying drawing, in which:—

Figure 1 shows the body of the support; Fig. 2 shows the same support to which is 110 attached the flexible connection; Fig. 3 shows in elevation and plan the upper shell;

Fig. 4 are similar views to Fig. 3 of the shell support; Fig. 5 shows the whole device fitted together.

In Fig. 1 the annular member *a* is the portion to which the elastic fabric is attached. The opening *b* serves for the passage of the pulling member carrying the button over which the stocking is passed.

The parts *c* and *c'* show suitable means for 10 retaining the flexible or resilient buckle and consist of two small tongues raised from the body of the support, the edge *e*, *f* of the lower portion of this member being turned over upon itself along its entire length.

15 As will be seen in Fig. 2 the clip or buckle acts in the following manner:

The joined ends of the flexible buckle or its reinforcement are engaged in the direction indicated by the arrow between the 20 raised tongues *c*, *c'* which are subsequently pressed down again tightly to retain the flexible portion between them; the flexible buckle is then placed in position reserved for it between the raised ends *m*, *n* which 25 are next turned down in such a manner as not to show the rough or cutting edges either externally or internally and further arranged not to press the flexible buckle.

The shell in Fig. 3 is then pressed tightly 30 at the rear of Fig. 2 on the parts *o*, *p*, *q* of the support and the member shown at Fig.

4 is fitted between the raised parts of this shell by placing the recess *l* at the bottom flat on top of the two branches of the flexible member. This fitting is secured to the device by tightening or pressing the extremities of the raised pieces on the shell as shown at Fig. 3. Fig. 5 shows the assembled parts and the attachment of the button carrying member.

40 I claim:—

1. In a suspender, a sheet metal body having an attaching loop at one end and a bendable portion at the opposite end, and further provided, near the center, with upstruck 45 tongues; a flexible loop having its ends attached to said tongues and secured near its ends in tubular members formed in the bendable portion of the body.

2. In a suspender, a sheet metal body having an attaching loop at one end and a bendable portion at the opposite end, and further provided, near the center, with upstruck 50 tongues; a flexible loop having its ends attached to said tongues and secured near its ends in tubular members formed in the bendable portion of the body, and a shell inclosing the central portion of the body, the 55 ends of the flexible loop and the inner ends of said tubular members.

PAUL PUGNIET.
